UNITED STATES PATENT OFFICE.

GODFREY L. SCHUETZ, OF ROCHESTER, NEW YORK.

FURNACE.

1,069,983.

Specification of Letters Patent. Patented Aug. 12, 1913.

Application filed April 5, 1912. Serial No. 688,757.

To all whom it may concern:

Be it known that I, GODFREY L. SCHUETZ, citizen of the United States, residing at Rochester, in the county of Monroe and State of New York, have invented certain new and useful Improvements in Furnaces, of which the following is a specification.

The object of my invention is to provide an improvement in furnaces, such furnaces as are used for case hardening the steel rings used for bearing surfaces in ball bearings, or for case hardening any other steel parts.

Another object of my invention is to provide a furnace that will secure an even distribution of heat on the parts that are to be heated and hardened.

Another object of my invention is to provide special facilities in the furnace for exposing the parts to be case hardened uniformly to the heat from all directions.

Another object of my invention is to provide turn tables in the furnace, on which the parts to be case hardened can be rotated and exposed to the heat of the furnace.

Another object of my invention is to provide a yielding floor or false bottom in the furnace on which the highly heated pieces of steel may be handled with safety and freedom from distortion or warping.

Another object of my invention is to provide a chute at the end of the furnace through which the finished parts may conveniently pass without exposure to the air from the furnace to the water tank where they are chilled.

Another object of my invention is to construct the furnace so that the charge of pieces to be chilled may be introduced at one end and taken out at the other end.

Another object of my invention is to construct the furnace with turn tables therein driven by a pneumatic motor, the source of power of which is the compressed air which feeds the flame that heats the furnace.

These and other objects of my invention will be fully illustrated in the drawings, described in the specification and pointed out in the claims at the end thereof.

In the accompanying drawings, Figure 1 is a side elevation of my improved furnace. Fig. 2 is a vertical longitudinal section through the furnace on the line 2^x—2^x in Fig. 3. Fig. 3 is a vertical transverse section through the furnace on the line 3^x—3^x in Fig. 1. Fig. 4 is a perspective view partly

broken away showing the general arrangement of the parts. Fig. 5 is a diagrammatic view of the piping that feeds the air blast to the furnace and the pneumatic motor. Fig. 6 is a perspective view of the pneumatic motor that is used for driving the turn tables of the furnace.

My improved furnace is built on a base plate 1 which rests upon a table 2 of any improved construction. On top of the table 1 is placed a layer of fire brick 3. On top of this base is erected a furnace having the ends 4 and 5 thereof formed of fire clay or fire brick and having the top 6 thereof also formed of fire clay or fire brick. The top 6 is supported by the side walls 7 and 8, as shown in Fig. 3. The outside of the furnace is covered by a metal shell 9, as is shown in cross section in Figs. 2 and 3. The top of the furnace is supported from this shell in any suitable or convenient manner.

Supported on the layer of fire brick 3 is a series of half round tiles 10, 10, on which is laid a layer of fire brick 11 which constitutes the floor of the furnace. The floor 11 will be supported by the half round tiles which will yield thereunder to any sudden impact, thus making the floor 11 somewhat elastic under a heavy impact.

At the right hand side of the furnace I place the charging door 12, which may be hinged or mounted to slide in any suitable manner. On the opposite end of the furnace is placed the door 14 which is preferably hinged at the top, which door is provided with the sight openings 15, 15 which are normally covered with swinging shutters, and with the sight opening 16 which is normally closed by a sheet of mica. This door is also provided with an opening 17 through which a rod can be introduced for the purpose of handling parts of steel within the furnace that are being heated.

The door 14 is mounted on a hood or casing 18 which is bolted to the furnace. In the bottom of this casing is pivotally mounted a trap 19. Below this trap is attached the chute 20, the purpose of which parts will presently be described.

Near the right hand end of the furnace, as shown in Fig. 4, the turn tables 20 and 21 are mounted. (See Figs. 3 and 4.) The top of these turn tables lies flush with the bottom of the furnace. These turn tables are made preferably of fire clay or any other suitable substance. They are supported in

cups 22 and 23, between which cups and turn tables is interposed a layer of heat insulating substance, preferably asbestos. The cups 22 and 23 are in turn supported by the shafts 24 and 25, which shafts in turn are supported in any suitable manner. A motor 30 is provided which consists preferably of two double ended blades set at an angle to each other, as is shown in Fig. 6, on both of which is blown a stream of compressed air, by which the rotation of the blades and the parts connected thereto is secured. The turn tables 20 and 21 are rotated by the motor.

15 Central of the furnace is provided openings 30, one on each side, through which is admitted a blast of air and oil, by the burning of which the furnace is heated. The furnace on each side is also provided with 20 the vent openings at the bottom, 31, 32 at one end and similar openings at the other end, through which the products of combustion are taken from the furnace at the floor and discharged from the walls of the furnace at the top.

25 I provide for the furnace a system of piping as follows: The pipe 40 connects with some source of supply of compressed air which is regulated by the valve 41. This 30 pipe connects with the distributing pipes 42 and 43, by which the compressed air is conveyed to the pneumatic motor. It also connects with the distributing pipes 44 and 45 which convey the air through the burners in the furnace. Suitable valves are placed in 35 each of these distributing pipes to regulate the flow of air therethrough. I also provide the pipe 50 which communicates with the source of the supply of oil, and through 40 which the oil is fed through the distributing pipes 51 and 52 to the burners. The oil and compressed air come together at the burners, the oil being atomized by the compressed air and the two are blown vertically into the 45 furnace against the roof where they are burned, for the purpose of heating the furnace.

50 The operation of my improved furnace is substantially as follows: The valves controlling the air and oil or other fuel are opened and the burner valves are set and the mixture of air and oil is blown vertically into the furnace against the roof of it. The blast of air and oil is ignited by a piece of 55 burning waste and as it begins to burn, it begins to heat the roof of the furnace which in turn increases the combustion, causing the oil to be completely and quickly burned. The charging door 12 is opened and a stack 60 of rings or other parts that are to be case hardened, is placed upon each of the turn tables 20 and 21. The door is then closed. The turn tables are then rotated, exposing the stack of steel plates uniformly to the 65 heat of the furnace on all sides. When the

furnace has been charged in this way the attendant will watch the operation of the furnace through the sight opening 16. The top plate of each of the stacks will heat the quickest, and as it approaches a suitable 70 temperature for tempering, the attendant will draw it from the top of the stack and place it on the floor of the furnace near the turn table, and as others are also drawn from the stack on the turn table to the floor of the 75 furnace, the plate or plates previously drawn from the stack will be advanced toward the door 14. The operator reaches in through the openings in the door with a hook for this purpose. After several minutes' 80 exposure to the heat of the furnace, one or more of the plates will be ready for removal from the furnace and in that case each plate as its heating is finished, will be drawn upon the trap 19 which will be tilted to discharge 85 the plate into the conveying chute 20, down which it will roll on its edge, passing through the opening 56 into a water tank not shown. In this way the plates are gradually removed from the turn table where 90 they receive their first heat, and are spread out on the floor of the furnace and then discharged into a water tank where they are chilled. As fast as each of the turn tables is emptied a fresh stack of plates may be put 95 thereon, and in this way the operation of the furnace may be carried on continuously.

Having thus described my invention, what I claim as new and patentable is as follows:

1. In a furnace, the combination of a casing lined with refractory material, doors at opposite ends thereof, a turn table in the bottom of said casing near one of said doors and means for continuously rotating said turn table, the top of said turn table lying 100 flush with the bottom of the furnace, said bottom extending for a considerable distance from the turn tables to the door at the opposite end of the furnace.

2. In a furnace, the combination of a casing lined with refractory material, one or more openings in the bottom of said casing, a turn table mounted to rotate in each of said openings, and a door adjacent to said turn table or turn tables, the bottom of said 115 furnace extending from said turn table a considerable distance to the opposite end of the furnace and a door at the opposite end of the furnace, both of said doors being above the floor.

3. The combination in a furnace of an elongated casing, a door at each of the opposite ends thereof, a turn table adjacent to the door at one end, the floor of the furnace extending continuously from said turn table 125 to the door at the opposite end of the furnace, a trap in the floor of the furnace adjacent to the opposite end, and a chute under said trap communicating with the furnace through said trap.

4. The combination in a furnace having a floor therein composed of refractory material, of openings therein in which turn tables are mounted to rotate, and means for continuously rotating said turn tables, said floor extending a considerable distance on one side of said turn tables, a door at each end of said furnace; and means for heating said furnace evenly throughout its length.
5. In a furnace, the combination of a casing lined with refractory material, a bottom in said casing, a turn table projecting through said bottom at one end thereof, said bottom extending from said turn table a distance substantially equal to or greater than the diameter of the turn table; a door at each end of said casing, an opening for delivering a blast to said furnace centrally of and transversely to said casing and vent openings at the ends of said casing.
6. In a heating furnace the combination of a furnace casing having a floor therein, said floor having centrally at the edges and on opposite sides thereof openings, means for blowing a combustible mixture through said openings, said mixture burning inside of the furnace and flues for drawing off the product of combustion from the furnace, said flues opening into the interior of the furnace through the sides at the bottom of the furnace, the ventilation of the furnace for the purpose of combustion and heating being confined to said openings and said flues.
7. In a heating furnace the combination of a furnace casing having a floor therein, said floor having centrally at the edges and on opposite sides thereof openings, means for blowing a combustible mixture through said openings, said mixture burning inside of the furnace, flues for drawing off the product of combustion from the furnace, said flues opening into the interior of the furnace through the sides at the bottom of the furnace and a door at each end of the furnace, the ventilation of the furnace for the purposes of combustion and heating being confined to said openings and said flues.
8. In a furnace for heating, the combination of a casing lined with refractory material, a bottom in said casing, a turn table projecting through said bottom at one end thereof, said bottom extending from said turn table toward the opposite end of the furnace and affording a surface on which the material to be heated in the furnace can rest for the final heating, and means for projecting a combustible blast vertically through openings located at the opposite edges of the floor of the furnace approximately midway of its length.
9. In a furnace for heating, the combination of a casing lined with refractory material, a bottom in said casing, a turn table projecting through said bottom at one end
10. The combination in a furnace for heating, the combination of a casing lined with refractory material, a bottom in said casing, a turn table projecting through said bottom at one end thereof, said bottom extending from said turn table toward the opposite end of the furnace and affording a surface on which the material to be heated in the furnace can rest for the final heating, means for blowing a combustible mixture into said furnace centrally thereof, and flues for exhausting the products of combustion, connecting with the interior of said furnace at the ends thereof.
11. In a furnace for heating, the combination of a furnace casing having one or more openings in the ends thereof for doors, said casing having openings in the bottom thereof and means for introducing a combustible mixture through said openings under pressure to cause it to blow upwardly along the sides and against the roof of the furnace, said casing having exhaust openings at the ends thereof, said openings being at or near the floor of the furnace, the ventilation of the furnace for the purposes of combustion and heating, being confined to the openings at or near the floor of the furnace.
12. In a furnace for heating, the combination of a furnace casing having one or more openings in the ends thereof for doors, said casing having openings in the bottom thereof, means for introducing a combustible mixture through said openings under pressure to cause it to blow upwardly along the sides and against the roof of the furnace, said casing having exhaust openings at the ends thereof, said openings being at or near the floor of the furnace, the sides and roof of the casing being otherwise without openings.
13. In a furnace for heating, the combination of a furnace casing having one or more openings in the ends thereof for doors, said casing having openings in the bottom thereof and means for introducing a combustible mixture through said openings under pressure to cause it to blow upwardly along the sides and toward the roof of the furnace, said casing having exhaust openings at the ends thereof, said openings being at or near the floor of the furnace, one of the openings for the introduction of the combustible mixture being located between two of the exhaust openings.
14. In a heating furnace, the combination

- of a furnace casing having a floor therein, openings in said furnace casing, means for introducing a combustible mixture through said openings under pressure to cause it to be blown into the furnace, said mixture burning inside of the furnace, flues for drawing off the product of combustion from the furnace, said flues opening into the interior of the furnace at the bottom of the furnace and being arranged in pairs on opposite sides of said furnace, and one or more turn tables arranged in the floor of the furnace between a pair of said flues.
15. In a furnace, the combination of a casing lined with refractory material, doors at opposite ends thereof, a turn table in the bottom of said casing and means for continuously rotating said turn table, the bottom of said furnace extending for a considerable distance from the turn table.
16. In a furnace, the combination of a casing lined with refractory material, doors at opposite ends thereof, a turn table in the bottom of said casing and means for continuously rotating said turn table, the bottom of said furnace extending for a considerable distance from the turn table, said furnace being adapted to permit the progressive advancement of the stock through the furnace from one door to the other.
17. In a furnace for heating, the combina-

tion of a casing having one or more openings in the sides thereof for doors, said casing having openings in the bottom thereof, means for introducing a combustible mixture through said openings under pressure to cause it to blow upwardly along the sides and toward the roof of the furnace, said casing having exhaust openings at the ends thereof, said openings being at or near the floor of the furnace, the sides and roof of the casing being otherwise without openings.

18. A furnace having a combustion chamber adapted to receive the stock and heat the same, said chamber having an imperforate top and a bottom perforated substantially midway of its length on its opposite sides, means for introducing a combustible mixture through said perforations under pressure to cause it to impinge the top of the furnace and to ignite against such top, said top being of a material to reflect the heat toward the floor of the furnace, and exhaust openings in the lower part of the furnace substantially at its ends for the products of combustion.

In testimony whereof I affix my signature in presence of two witnesses.
